UNITED STATES PATENT OFFICE

AUGUST HEINRICH GERMER, OF HAMBURG, GERMANY

TYPE CARRIER FOR STAMPING PRESSES

Application filed October 15, 1926, Serial No. 141,782, and in Germany December 10, 1925.

In stamping-presses for producing bills, placards, posters, price-lists and the like, which are made of cardboard, and in which the letters or signs are produced by punching, embossing or impressing, the types are placed on straight edges, which are slideable in slots of two guide rails, which slots are closed at their ends. These guide rails are attached to the two sides of the slideable stamping plate. Since the straight edges cannot be taken out the placing of the set of types on the stamping-press must be carried out in an inconvenient and inexpedient manner. For the same reason the set of types can only be arranged with the lines transverse to the direction in which the stamping-plate is inserted. The length of the guide rails corresponds to the breadth of the stamping-plate in the direction of its insertion; therefore the set of types may only contain two to four lines. If the bill or placard to be stamped is intended to have a larger number of lines the remaining lines must each be stamped by a separate operation, whereby the bill is to be advanced after every operation for the breadth of a corresponding line according to judgment. Of course it will be understood that it is very difficult thereby to secure an even or harmonic spacing of the lines.

According to the invention a carrier is provided for the straight edges, which are supposed to receive the types, the carrier having the shape of a frame, on which the straight edges are to be placed. Thus these straight edges are replaceable, and when placed on the stamping-plate can be slid and removed therefrom.

The type carrier or setting-frame is placed on a working table and then the types may be set in a convenient manner on the straight edges, the latter being adjusted on the setting frame. The setting frame enables the setting of the straight-edges also parallel to the direction of insertion. In this case long narrow bills or placards can be stamped with a larger number of transverse lines in a single operation. The setting frame in its outer position on the stamping-plate is adapted to be raised to the necessary extent from the plate carrier by a lifting and holding device

to allow card-board with coloured paper below the set of types on the stamping-plate, whereupon by lowering the setting frame, the set of types engage the card board.

In the drawing a stamping-press is shown 55 having a carrier for the set of types constructed according to the invention by way of example.

Fig. 1 is a sectional elevation of the stamping-press, and 60

Fig. 2 a plan of the same.

Fig. 3 is a side view of the press partly in section.

Fig. 4 is a fractional side view showing a different position from that shown in Fig. 3, 65 and

Fig. 5 is a view from below of the parts shown in Fig. 4.

Fig. 6 is a plan showing the setting frame placed on the stamping-plate at right angles 70 to Fig. 2.

In the stamping-press shown in the drawing the stamping-plate *a* is arranged by the aid of guide rails slideably on the table *d*, which by an eccentric shaft *b* is adapted to be raised towards the upper part *c* of the press. The table *d* has a prolongation *d'* on one side. On the stamping-plate *a* a setting frame *e* may be placed, the lateral parts of which embrace the stamping-plate laterally. 75 The setting frame is square, that is to say, its transverse sides are the same distance from one another as the lateral sides. All sides have a rectangular cross section, and their horizontal faces have the same breadth. 85

The straight edges *f* are provided at their ends with heads *g* which on their undersides have a groove by which the straight edges can be placed on the setting frame. By the aid of screws which pass through the heads *g* the straight edges when adjusted may be locked to the setting frame *e*. This allows of the straight edges *f* being placed on the lateral sides of the frame as well as on the transverse sides of the setting frame. In the first case the lines of the set of types run transversally to the direction in which the stamping plate is inserted, (Figs. 1-3 and 4), and in the other case parallel to this direction, (Fig. 6). 95 100

At both sides of the prolongation d' of the table d two arms h are attached to a common shaft i which arms are provided with handles k at their outer ends. The arms h 5 may be oscillated into a horizontal position and in this position locked by a turn-buckle l , catching hold of a rod m , connecting the arms. In Fig. 5 the underside of the prolongation d' of the table and the turn-buckle l is shown.

When placed on the prolongation of the table the setting frame with its lateral sides is supported by the arms h and thus is held at such a distance from the stamping-plate 15 a that the types each resting on two straight edges f are situated at a distance above the stamping-plate. The transverse sides of the setting frame which with their upper faces are flush with the upper face of the lateral frame sides have a less height than the latter. Therefore they do not engage the stamping-plate, when the setting frame is supported 20 by the arms h (Fig. 4). The intermediate space between the stamping-plate and the 25 transversal sides of the frame thus formed enables the introduction of the card board to be stamped and the coloured paper placed thereon under the set of types. When now the arms h are lowered the setting frame e 30 (Fig. 3) also lowers, whereby the stamping types engage the card board with or without the coloured paper, but are raised slightly from the straight edges. Now the stamping plate may be inserted into the press. After 35 the stamping has been performed the stamping plate is withdrawn by a handle n attached thereto, whereupon the arms h are turned into horizontal position and locked by the turn buckle l . The setting frame is 40 thus raised and may be withdrawn from the card board together with the set of types.

The setting frame e is preferably square and projects from the stamping-plate a in front, when placed thereon (Figs. 2, 3 and 45 4). Thus it is broader than the stamping-plate in the direction of insertion. When a card is intended to be stamped with more lines than the stamping-plate is able to take up in one operation the following method is 50 to be carried out. The types for all lines are placed on the straight edges f . When then the card board to be stamped or embossed together with the sheet of coloured paper is placed on the stamping-plate the 55 latter is inserted into the press and the stamping of the types on the stamping-plate is carried out. Thereupon the stamping-plate is again withdrawn and the setting frame together with the set of types and the 60 card board still adhering to the latter owing to the stamping operation is moved forward on the stamping-plate in such wise, that the remaining lines of the types are placed on the stamping-plate. To make sure that this 65 forward movement is carried out in the prop-

er manner and conveniently one side of the frame-like handle n of the stamping-plate is provided with a number of gaps o or is serrated and the setting frame on this side is provided with a tooth p . On moving the 70 setting frame forwardly the proper distance between the first group of lines and the second group of lines is secured by allowing the tooth p to engage in the corresponding gap o .

In order to allow lines to be stamped or 75 embossed at an angle the heads g of the straight edges f may be attached to the latter rotatably. One of the heads in this case will have to be slid able in longitudinal direction of the straight edges. 80

I claim:—

1. A type carrier in stamping-presses for punching embossing or impressing letters or the like in cardboard and arrangement of same in the stamping-press comprising a 85 rectangular frame which is adapted to be removably mounted on the stamping-plate which supports the work piece and means forming straight edges serving for setting the types adapted to be removably mounted on 90 the setting-frame.

2. A type carrier according to claim 1, in which the lateral sides of the setting frame laterally lap over the stamping-plate and that the underface of the transverse sides of the frame is higher than the underface of 95 the lateral sides.

3. A type carrier according to claim 1, the setting frame being square, in which the lateral sides of the setting frame laterally lap over the stamping plate and that the undersurface of the transverse sides of the frame is higher than the undersurface of the lateral slides the straight edges being provided at their ends with rotatable heads having a 100 groove on the underside by the aid of which the straight edges are adapted to be placed on the lateral or on the transversal sides of the setting frame.

4. A type carrier as claimed in claim 1 110 provided with a tooth adapted to engage notches on the stamping plate to enable the setting frame to be adjusted.

5. A type carrier as claimed in claim 1 115 including a handle for the stamping plate, the type carrier being provided with a tooth adapted to engage a notch on said handle to enable the setting frame to be adjusted.

6. A type carrier as claimed in claim 1 including a press table having a prolongation, two arms rotatably adapted to said prolongation upon which the setting frame is adapted to rest so as to be in raised position when said arms are adjusted to horizontal position and means for locking said arms in said positions. 120

7. In a press for forming embossed tickets and the like by punching out characters in paper and impressing them on card-board, a 125

slidable die-plate for supporting the work piece a rectangular frame adapted to be laid on said die-plate so as to be instantly removable, and rules serving for setting the types removably fitted upon said frame.

8. In a press for forming embossed tickets and the like by punching out characters in paper and impressing them on card-board, a slidable die-plate for supporting the work piece a rectangular frame adapted to be laid on said die-plate so as to be instantly removable, rules serving for setting the types are removably fitted to said frame, said frame projecting beyond the plate in the direction away from the press, the sides thereof extending in the direction away from the press embracing the plate; the under faces of the two other sides being higher than the under faces of the two first named sides.

9. In a press for forming embossed tickets and the like by punching out characters in paper and impressing them on card-board, a die plate for holding the work piece a rectangular frame adapted to be laid on said die-plate so as to be instantly removable, rules serving for setting the types removably fitted to said frame, said frame projecting beyond the plate in the direction away from the press, the sides thereof, extending in the direction away from the press, embracing the plate; the under faces of the two other sides being higher than the under faces of the two first named sides, the heads of the rules being equally adapted to catch over the sides of the frame extending in the direction away from the press or over the two other sides.

10. In a press for forming embossed tickets and the like by punching out characters in paper and impressing them on card-board, a die-plate for holding the work piece a rectangular frame adapted to be laid on said die-plate so as to be instantly removable, rules serving for setting the types removably fitted to said frame, said frame projecting beyond the plate in the direction away from the press, the sides extending in the direction away from the press embracing the plate; the under faces of the two other sides being higher than the under faces of the two first named sides so that, the heads of the rules are equally adapted to catch over the sides of the frame extending in the direction away from the press or over the two other sides, the said heads being so mounted on the rules as to allow lines to be embossed at an angle.

11. In a press for forming embossed tickets and the like by punching out characters in paper and impressing them on card-board, a die-plate for holding the work piece a rectangular frame adapted to be laid on said die-plate so as to be instantly removable, rules serving for setting the types removably fitted upon said frame, a member upon the die-plate having notches therein, and a tooth

upon the frame engageable selectively in said notches.

12. In a press for forming embossed tickets and the like by punching out characters in paper and impressing them on card-board; a die-plate for holding the work piece a rectangular frame adapted to be laid on said die-plate so as to be instantly removable, rules serving for setting the types removably fitted upon said frame, a tooth upon the frame, and a handle adjustable to operate said die-plate and having a notch in which the tooth is engageable.

13. In a press for forming embossed tickets and the like by punching out characters in paper and impressing them on card-board, in combination with an extension of the table of the press a die-plate for holding the work piece, a rectangular frame to be laid upon said die-plate of the press and free to be instantly removable therefrom, said frame being disposed with its sides projecting in a direction away from the press, arms pivotally mounted on the extension of the table, the said sides of the frame bearing on the arms whereby the frame will be moved to raised position when said arms are raised to horizontal position and locked in said position so that the work piece may be inserted upon said die-plate.

14. In a press of the type described, a platen, a frame mounted upon said platen and removable therefrom, type securing means secured to said frame and means for raising said frame with the type disposed therein above said platen so that a work piece may be inserted below said frame upon said platen.

In testimony whereof I have signed my name to this specification.

AUGUST HEINRICH GERMER.
